ARTHUR M. ALVORD, OF NEW ROCHELLE, NEW YORK, ASSIGNOR TO ALVORD AND SWIFT, OF NEW YORK, N. Y., A CORPORATION OF NEW YORK.

THAWING MATERIAL IN CARS.

1,357,305.

Specification of Letters Patent.

Patented Nov. 2, 1920.

Application filed March 7, 1918. Serial No. 221,043.

To all whom it may concern:

Be it known that I, ARTHUR M. ALVORD, a citizen of the United States, residing at New Rochelle, in the county of Westchester, State 5 of New York, have invented certain new and useful Improvements in Thawing Materials in Cars; and I do hereby declare the following to be a full, clear, and exact description of the invention, such as will enable others 10 skilled in the art to which it appertains to make and use the same.

The present invention relates to improvements in thawing material in cars, and while particularly intended for thawing coal 15 frozen in coal cars may be used for thawing any material that may be frozen in the car.

The usual practice in thawing coal or other material contained in cars is to inject steam into the mass of material by means of 20 a pointed tool having apertures in its sides and connected to a steam hose, but this method is slow and wasteful of steam, since a considerable amount of the latter simply rises through the space between the tool and 25 the material without penetrating and thawing the coal. It has also been proposed to run the cars into heated chambers and let them remain until the material therein has thawed out, but this method involves the 30 construction of special buildings, and at best requires considerable time for the heat to warm the entire mass of material.

It is an object of the present invention to provide a construction in which steam may 35 be supplied at a number of points throughout the body of a car in position to penetrate the entire mass of material therein, so that the latter may be rapidly and uniformly thawed. This and other objects of the in- 40 vention are attained by equipping the car with a practically indestructible system of pipes and valves, through which steam may be supplied from an external source. The valves are preferably located at various 45 points throughout the bottom of the car, and are automatically opened by the pressure of the steam so that no manipulation is required, after the piping system has been connected to a source of steam supply.

50 The conditions under which such a system will be used are such that not only is it essential that the elements of the system shall be simple, rugged and automatic, and afford a minimum opportunity for injury to and 55 derangement of the parts; but provision

must be made for a self-cleaning and self-thawing action of the system. To this end the system of the present invention is such that simple, standard, rugged and interchangeable parts are used and provision is 60 made for an initial cleaning and thawing blowout of the system followed by an automatic opening of the inlet valves under the pressure of the heating medium. Preferably, also the inlet valves controlling the 65 passages into the car are restricted, with respect to the piping of the conduit system, so as to cause the heating medium to flow into the frozen material at high velocity and pressure. 70

The particular nature of the present invention will appear more clearly from a description of a preferred embodiment thereof as shown in the accompanying drawings in which Figure 1 is a plan view of a car; Fig. 75 2 is an elevational section along the line 2-2 of Fig. 1; Fig. 3 is a transverse section along the line 3-3 of Fig. 1, and Fig. 4 is a sectional view of the automatic valve.

The car shown in the drawings is of the 80 ordinary steel gondola type used for carrying coal, ore or other material, and comprise a center sill 10 and the usual bolsters 11 for supporting the body of the car, which, as is customary in constructions of this kind, is 85 provided with a bottom 12 sloping from each end toward the center of the car and a central sloping portion 13 which serves to deflect material in either direction toward the doors 14 which are hinged at 15. The particular construction of the car forms no part 90 of the present invention, and hence need not be described in greater detail.

In accordance with the present invention, I provide on each side of the car, and preferably attached to the end sills a pipe 16 running the entire length of the car. One end of each pipe is provided with a valve 17, and a coupling adapted to be connected to a hose through which steam may be supplied 100 from an external source. The other end of the pipe is closed by a cap 18, and preferably the valves and couplings should be arranged at diagonally opposite corners of the car as shown most clearly in Fig. 1. Each of the 105 pipes 16 may be given a slight inclination toward the center of the car, in order to provide for the drainage of water of condensation which may be discharged through a steam trap 19 of any suitable construction. 110

It will be understood, however, that the steam traps may be located at any other appropriate point in the system.

Branch pipes 20 are tapped off of the main pipe 16 along each side of the car, and at their ends these branch pipes are connected to transverse pipes 21 attached to the under side of the car bottom in any convenient manner, as by means of clamps 22 as shown in Fig. 1. In the space beneath the central sloping portion 13 of the bottom of the car is a transverse pipe 23 connected to the main pipes 16 on each side of the car by vertical pipes 24. Branching off from the pipe 23 are short pipes 25 which extend toward the sloping sides of this portion 13 of the car bottom.

For controlling the admission of the heating medium to the material within the car, I provide automatic valves 26 of the construction shown in Fig. 4, and which may be inserted in the various pipes of the system at convenient points as indicated to supply sufficient heat to the mass of material within the car. Each of the valves comprises a standard cross 27 to which the pipes may be connected, or in case the valve is used at the end of a pipe, a T may be employed or one of the outlets may be closed with a suitable plug or cap. Into one outlet of the cross is fitted the special valve-casing 28 which is attached to the bottom of the car, preferably in such a manner that the upper end of this casing is flush with the floor of the car. The casing 28 is provided at its upper end with a small valve seat 29, and coöperating with this seat is a valve 30 mounted upon the end of a stem 31 which is guided in a spider 32 located at the lower end of the casing 28. The lower end of rod 31 is guided in a spider 33 within a valve-seat fitting 34 inserted into the end of the casing 27. A spring 35 surrounding the upper end of the valve stem, and retained in place between the valve 30 and the spider 32 holds the valve 30 normally against its seat. Attached to the valve stem near its lower end is a second valve 36 which when the valve 30 is in its normal position is raised from its seat on the fitting 34. The construction of the automatic valve is such that when the steam or other fluid enters the union 27, it will tend to drive out all water of condensation, dirt and obstructions through the openings in the spider 33, and to thaw out the valves, if they are frozen. The steam will be discharged through this spider until its pressure within the chamber reaches a predetermined amount sufficient to cause the valve 36 to be depressed into contact with its seat against the effect of the spring 35. When this occurs, the steam will enter the body of the car through the opening between valve 30 and its seat 29 at high velocity and pressure.

In practice, the last named opening should be sufficiently small so that there will be little or no tendency for material in the car to fall into this opening as it begins to be thawed under the influence of the steam.

When a car provided with the improvement of the present invention contains a load of frozen material such as coal, the car will be run to a locality where a source of steam supply may be connected to one or the other of the main feed pipes 16. The corresponding valve 17 is opened and steam allowed to enter the pipe system. After the initial blow-out, and when the pressure in each of the automatic valves reaches the predetermined amount for which the spring of the valve has been set, say about ten pounds, the valve will open and allow steam to enter the mass of material at relatively high pressure, say seventy or eighty pounds, gradually thawing the same as it works its way upward through the mass. If during the thawing operation, or at any other time, water or dirt collects in the automatic valve, it will drain out through the spider 33 as soon as the steam pressure is cut off, so that the valve 36 is lifted from its seat, or will be blown out by the steam at the next operation. Any water of condensation which may accumulate in the pipes of the system will ultimately drain into the main feed pipes and be discharged through the traps 19.

While the apparatus has been described particularly in relation to a coal car and depending upon the use of steam as a heating medium, it will be understood that it is equally adapted for any kind of cars in which material that may become frozen is transported, and also instead of using steam any other suitable heating medium may be supplied to the pipe system. So far as the valves 26 are concerned, they may be located at any number of points as desired, and it is not intended that their number or their location shall be limited by the showing in the figures.

I claim:

1. In a car equipped for thawing out material frozen therein, the combination of a heating medium conduit system and distributed valves having restricted velocity increasing passages between said system and the lower interior portion of the car to blow the heating medium at high velocity and pressure into the body of frozen material within the car.

2. In a car equipped for thawing out material frozen therein, the combination of a heating medium conduit system mounted on the exterior of the car and distributed valves in said system for controlling the admission of the heating medium into the lower interior portion of the car, to thaw out material frozen therein.

3. In a car equipped for thawing out ma-

terial frozen therein, the combination of a heating-medium conduit system mounted on the exterior of the car and distributed automatic valves in said system communicating with the lower interior portion of the car for permitting the heating medium to be discharged into the body of the frozen material within the car.

4. In a car equipped for thawing out material frozen therein, the combination of a plurality of casings mounted on the outside of the car and provided with ports communicating with the interior thereof, a valve in each casing for normally closing the port therein, pipes mounted on the outside of the car and connected to said casings for supplying a heating medium thereto, and means associated with each valve for opening the same when the pressure of said medium reaches a predetermined value.

5. In a car equipped for thawing out material frozen therein, the combination of a plurality of casings mounted on the outside of the car and provided with ports communicating with the interior thereof, a valve in each casing adapted to coöperate with the port therein, a valve stem slidably mounted in said casing and to one end of which the valve is attached, a spring for holding said valve in position to close the port, pipes mounted on the outside of the car and connected to said casings for supplying a heating medium thereto, and means associated with each valve stem for overcoming the effect of said spring to open the valve when the pressure of said medium reaches a predetermined value.

6. In a car equipped for thawing out material frozen therein, the combination of a heating-medium conduit system, and distributed self-cleaning valves connected to the system and opening into the interior of the car beneath the frozen material therein.

7. In a car equipped for thawing out material frozen therein, the combination of a heating-medium conduit system and dis-

tributed self-cleaning valves connected to the system and opening into the interior of the car beneath the frozen material therein, said valves having a blow-out discharge opening permitting an initial cleaning blow-out upon the application of the heating medium to the system.

8. In a car equipped for thawing out material frozen therein, the combination of a heating-medium conduit system, distributed self-cleaning valves connected to the system and opening into the interior of the car beneath the frozen material therein, said valves having a blow-out discharge opening permitting an initial cleaning blow-out upon the application of the heating medium to the system, and means adapted to open the passages into the car when the pressure of the heating medium in the valves reaches a predetermined value after the initial blow-out.

9. In a car equipped for thawing out material frozen therein, a heating-medium conduit system mounted on the exterior of the car and distributed valves having restricted velocity increasing outlet openings into the lower interior portion of the car.

10. In a car equipped for thawing out material frozen therein, a heating-medium conduit system mounted on the exterior of the car and distributed normally closed valves having restricted velocity increasing outlet openings into the lower interior portion of the car and means actuated by the pressure of the heating medium for opening said valves automatically.

11. In a car equipped for thawing out material frozen therein, a heating-medium conduit system mounted on the exterior of the car and distributed valves having restricted velocity increasing outlet openings into the lower interior portion of the car and flush with the floor thereof.

In testimony whereof I affix my signature.

ARTHUR M. ALVORD.
